(57) **CLAIM**

The ornamental design for a culture device, as shown and described.

DESCRIPTION

FIG. 1 is a front elevational view of a culture device showing our new design;

FIG. 2 is a rear elevational view thereof;

FIG. 3 is a left side elevational view thereof;

FIG. 4 is a right side elevational view thereof;

FIG. 5 is a top plan elevational view thereof;

FIG. 6 is a bottom elevational view thereof;

FIG. 7 is a cross-sectional view thereof taken along line 7-7 of FIG. 1;

FIG. 8 is a front elevational view thereof in an open position; and,

FIG. 9 is a right side elevational view thereof in an open position.

The broken lines in the drawings depict portions of the culture device that form no part of the claimed design.
